UNITED STATES PATENT OFFICE.

JOSEPH WIESER, OF BROOKLYN, NEW YORK, ASSIGNOR OF ONE-HALF TO
KARL FINK, OF NEW YORK, N. Y.

PNEUMATIC MOTOR.

SPECIFICATION forming part of Letters Patent No. 693,198, dated February 11, 1902.

Application filed December 6, 1900. Renewed November 14, 1901. Serial No. 82,221. (No model.)

To all whom it may concern:

Be it known that I, JOSEPH WIESER, a citizen of the United States, residing in New York, in the borough of Brooklyn and State of New York, have invented certain new and useful Improvements in Pneumatic Motors, of which the following is a specification.

This invention relates to an improved pneumatic motor for self-playing mechanical musical instruments, the motor being so constructed that a multiple of pneumatics, preferably three or more, are arranged in connection with a rotating crank-shaft, suction valve-chests, and rotary slide-valves, channels connecting said pneumatics with the suction-chests, so that the pneumatics are successively exhausted and the power produced by the same transmitted to the crank-shaft, so that uniform power is available for moving the perforated music-sheet of the mechanical musical instrument or for winding up the same after the same is played.

The invention consists of a pneumatic motor comprising a series of pneumatics, a rotary crank-shaft, the cranks of which are connected with said pneumatics, stationary valve-chests connected by suction-channels with the main suction-chest of the musical instrument, said crank-shaft passing through the valve-chests and valves, and rotary slide-valves connected with the cranks of the crank-shaft, said cranks being arranged at suitable angles to each other around the shaft, so as to produce the successive actuation of the rotary slide-valves and pneumatics and the transmission of these actuations to the crank-shaft, from which the power is transmitted to the winding-up rolls of the perforated music-sheet, as will be fully described hereinafter, and finally pointed out in the claims.

In the accompanying drawings, Figure 1 represents a front elevation of my improved pneumatic motor. Figs. 2 and 3 are vertical transverse sections on lines 2 2 and 3 3, Fig. 1. Fig. 4 is a section on line 4 4, Fig. 1. Fig. 5 is an enlarged detail side elevation showing the slide-valve and its connection with one of the pitmen or connecting-rods. Fig. 6 is a vertical transverse section on line 6 6, Fig. 5. Figs. 7, 8, and 9 are side elevations of the rotary slide-valve and its pitman,

showing, when taken with Fig. 5, the position of the same at every quarter part of a rotation. Fig. 10 is a vertical transverse section on line 10 10, Fig. 8. Fig. 11 is a perspective view looking toward the inside of the slide-valve; and Figs. 12, 13, and 14 are respectively a vertical section on line 12 12, Fig. 1, a plan view, and a vertical section on line 14 14, Fig. 12, of the speed-regulating valve by which the suction action of the main suction-chest on the pneumatics is regulated.

Similar letters of reference indicate corresponding parts.

Referring to the drawings, A represents the supporting-board of my improved pneumatic motor. This board may be arranged in horizontal, vertical, or any other suitable position, according to requirement. A number of power-pneumatics B are attached to the supporting-board A, there being, preferably, three pneumatics for each motor. The movable member of each pneumatic is connected by a pitman or connecting-rod C with a crank C' on the driving-shaft S, said cranks C' being arranged on the shaft S for three pneumatics at an angle of one hundred and twenty degrees to each other, so that each pneumatic produces motion for one-third of the rotation of the driving-shaft S. The shaft S passes through valve-chests D of rotary slide or disk valves F, which are suitably fixed to and arranged below the supporting-board A, each valve-chest being connected by a channel d with the interior of the power-pneumatics and by a second channel e with the suction-chest E, that is connected with the well-known main suction-chest of the mechanical musical instrument, which main suction-chest exerts a constant suction action on the suction-chest E and the channels and pneumatics connected therewith. Each crank C' of the driving-shaft S is provided with a slotted or bifurcated end, which is clamped by screw C^X loosely on the crank-pin d' on the crank of the rotary slide-valve F, said slide-valve being shown in detail in Fig. 11, and provided with a segment or other suitable opening f and with a segmental recess f' in its inner face that extends in a circular channel f² around the hub of the rotary slide-valve F, as shown in Fig. 11. Said opening f opens

into an arcuate or elongated recess f^x in the under side of the valve F, but diametrically opposite the recess f' . The rotary slide-valve F is provided at a point opposite to its point 5 of connection with the pivot-pin d' of the crank C' with a second socket-hole d^2 , similar to the one in which the pin is inserted, but which is hid from view, so that the pivot-pin d' of the crank C' can be connected with one 10 or the other of the opposite socket-holes in the rotary slide-valve, according as the pneumatic motor is to be run in one or the opposite direction. This is readily adjusted when the parts of the pneumatic motor are assembled 15 and the same properly connected with the parts of the mechanical musical instrument with which it is used.

The valve-chest is provided with a projecting circular portion D', of approximately the same size as the rotary slide-valve F. The opening f, recess f^x , and recesses $f' f^2$ move over a segmental opening f^3 and two segmental openings f^4 in the projecting portion D' of the valve-chest, said openings $f^3 f^4$ communicating, respectively, with the angular channels d and e , that communicate with the power-pneumatics and suction-chest E, as shown in Fig. 2. When, therefore, the driving crank-shaft is rotated, the power-pneumatics will follow, by reason of their connection with the cranks, successively one after the other the motion of the cranks. This produces the passage of the opening f and recess f^x over the opening f^3 (see Figs. 8 and 10) 30 and by the simultaneous action of the crank and pitman of the pneumatic the expansion of the pneumatic, so that atmospheric air is sucked therein. By continuing the motion of the driving-shaft the recesses f^x of 35 the valve are placed out of register and connection of the interior recesses $f' f^2$ with the openings $f^3 f^4$ established, so that the air in the pneumatics is placed under the suction action of the suction-chest E, which produces 40 the immediate collapse of the pneumatic, and thereby the impulse of the same on the crank-shaft. These two positions of the rotary slide-valves are shown, respectively, in Figs. 45 8 and 5, the intermediate positions in Figs. 5 and 9 showing the position of the slide-valve relatively to the ports of the stationary valve-chest, during which, except as now to be stated, no connection between the suction-chest and pneumatic is permitted. The 55 various phases of motion which take place will be clearly seen from Figs. 5 to 10, assuming that at the first phase the pneumatic is being collapsed. In the position shown in Figs. 5 and 6 suction will be exerted by the 60 suction-chest E, through the channel e, openings f^4 , recesses $f^2 f'$, opening f^3 , and channel or duct d on the pneumatics, thus collapsing the latter, and this motion is interrupted as soon as the valve has been rotated 65 into the position shown in Fig. 7, in which position the recess f' of valve F has passed the opening f^3 in the valve-chest. Arriving

in this position, the recess f^x in the valve meets the opening f^3 in the valve-chest, so that while the valve is moving through the 70 position shown in Fig. 8 and to about the opposite position in Fig. 9 the suction is shut off and atmospheric air passes through the opening or port f, recess f^x , opening f^3 , and channel d to the pneumatic, so as to expand 75 it. On arriving at the position shown in Fig. 9 the recess f' communicates with opening f^3 , so that suction is exerted on the pneumatic, this suction continuing until f' has passed opening f^3 . As the action of the various 80 pneumatics takes place successively in the form shown, one at each one-third rotation of the driving-shaft, three actuations of the pneumatics are produced for each rotation of the shaft, so that rotary motion is imparted 85 thereto by the impulses imparted to the same by the pneumatics, which motion of the driving-shaft is transmitted by a pulley and belt to the pulleys on the shafts of the unwinding and winding-up rolls of the music-sheet, so that the same can be either unrolled 90 or rewound on its roll, according as the belt is shifted to one roller-shaft or the other.

The speed of the motor is regulated by means of a speed-regulating device which is 95 arranged at one end of the suction-chest E, so as to control the suction action. This regulating device is composed of a stationary casing H, fixed to the suction-chest E and having a D-shaped interior cross-section, and a 100 slide-valve h, provided with openings h', that register with openings h^2 in the stationary D-shaped casing, and openings o, leading to the suction-chest E. The slide-valve h is provided with a stem h^3 , that passes through the 105 casing and has a button or handle h^4 at its outer end and so that it can be moved in its casing to open the openings leading into the suction-chamber E to a greater or less extent, so as to regulate thereby the suction action 110 exerted on the valve-chest and the power-pneumatics B. When the openings h' in the slide-valve are in full register with the openings in the stationary casing, the full suction action is exerted on the pneumatics, and thereby 115 the greatest speed imparted to the pneumatic motor, while when the openings in the slide-valve are placed partly out of register, so that the communicating openings between the suction-chest E and main suction-chest 120 are reduced in size, the speed of the motor is correspondingly reduced until by the non-registering of the openings in the slide-valve with the openings in the suction-chest the 125 total interruption of the functioning of the motor is produced.

The advantages of my improved pneumatic motor over the motors heretofore in use in which the valve action is produced by a reciprocating slide-valve are, first, that the rotary motion of the slide-valves is accomplished 130 with greater smoothness, so that the dead-points are overcome easier, while the successive action of the pneumatics on the

- driving-shaft at three or more points of its rotation produces the effective rotary motion of the slide-valve without any dwells or jerks of the same. Another advantage is that the 5 motor can be so adjusted as to be run in one or the other direction, which may be of advantage in many cases, according to the position of the motor in the mechanical musical instrument with which the same is used.
- 10 The tight fitting of the rotary valve to the stationary portion of the valve-chest is produced by the suction action of the main-chest, which causes the air-tight working of the rotary slide-valve on the stationary valve-chest, but, if desired, a special spring may be interposed between the rotary slide-valve and crank adjacent thereto, so as to hold the 15 valve always in position on the face of the valve-chest. Another advantage is that the 20 connecting-rods between the cranks and crank-shaft and pneumatics can be readily disconnected from the crank-shaft by loosening the split or bifurcated end of the same, so that the connecting-rods can be slid over 25 the wrist-pin of the crank and be easily replaced thereon and tightened up when they are reconnected with the cranks.
- Having thus described my invention, I claim as new and desire to secure by Letters 30 Patent—
1. The combination, with a plurality of stationary valve-chests, a suction-chest con-
- nected therewith, and an equivalent number of pneumatics also connected with the valve-chests, of a crank-shaft connected with the 35 movable members of the pneumatics and passing through the valve-chests, and rotary valves fixed at suitable intervals apart on said shaft and working each on one face of each of the valve-chests, said valves and 40 valve-chests being constructed to alternately admit air and shut it off from the pneumatics, substantially as set forth.
2. The combination, with a plurality of stationary valve-chests, each constructed with 45 suitable openings, a suction-chest connected directly with one of the said openings, and an equivalent number of pneumatics connected directly with the other of said openings, of a crank-shaft connected with the 50 movable members of the pneumatics and passing through the valve-chests, and rotary valves on said shaft, working each on one face of each of the valve-chests, each valve being provided with an air-inlet opening and 55 constructed with a recessed inner face, substantially as set forth.

In testimony that I claim the foregoing as my invention I have signed my name in presence of two subscribing witnesses.

JOSEPH WIESER.
